UNITED STATES PATENT OFFICE.

WILLIAM W. BRADLEY, OF WATERBURY, CONNECTICUT, ASSIGNOR OF ONE-HALF TO
WILLIAM L. DAY, OF SYRACUSE, NEW YORK.

BEAD-CHAIN.

1,051,384.

Specification of Letters Patent. Patented Jan. 28, 1913.

Application filed January 12, 1912. Serial No. 670,755.

To all whom it may concern:

Be it known that I, WILLIAM W. BRADLEY, a citizen of the United States, and a resident of Waterbury, in the county of 5 New Haven and State of Connecticut, have invented certain new and useful Improvements in Bead-Chains, which improvements are fully set forth in the following specification.

- 10 This invention relates to improvements in chains, and particularly chains of that class commonly known, by reason of the same comprising flexibly united globulous or spherical members, as bead-chains; and its 15 object is to provide a bead-chain which shall be durable, attractive in appearance, characterized by the utmost flexibility, and which shall possess certain well-defined advantages over prior analogous devices.
- 20 The invention consists in the details and parts whereby, together with the novel disposition and relative arrangement of said parts, the attainment of the foregoing object is rendered practicable, all of which will 25 be hereinafter more specifically referred to and set forth in the appended claims.

The invention is clearly illustrated in the accompanying drawings, wherein similar reference-numerals denote like parts 30 throughout the respective views, as to which:

Figure 1 is a view in elevation of a bead-chain embodying my said improvements. Fig. 2 is an enlarged sectional view of a 35 portion of my improved chain, the section being taken diametrically through the several spherical members thereof. Fig. 3 is a view similar to Fig. 2, save that the connecting stems of the chain are collectively 40 turned ninety degrees from the position they are there shown as occupying. Fig. 4 is an enlarged detail view showing a portion of the prepared stock made use of in the formation of my improved chain. Fig. 5 is a 45 detail view, partly in section, showing more particularly the segmental shoulder or shoulders with which each of the connecting stems of my improved chain is provided, the section being taken transversely through

the body of one of said stems and the scale 50 being still further enlarged.

In the fabrication of so-called bead-chains, it has been the practice to unite the spherical members thereof by means of connecting stems, each of which is provided at 55 its opposite end-portions with an annular shoulder continuously encircling the body thereof. This, whether the working face of said shoulder be flattened at right angles, or rounded or flattened at an inclination, to 60 the axis of the body of said stem, all as heretofore proposed, is objectionable, for the reason that, the continuous shoulder being made use of, the diameter of the opening by 65 way of which each connecting stem enters either of the spherical members coöperating therewith being kept within limits proper to insure the most attractive appearance of the completed chain, and the latter being tautened, as under a substantial pull length- 70 wise thereof, deflection of any of the stems made use of, in any direction whatsoever relatively to either of the spherical members coöperating therewith, and hence the general flexibility of the completed chain, will 75 be limited, not alone to the excess of diameter of the opening aforesaid over the diameter of the stem lying therein, but largely and more seriously by the shoulder aforesaid, the latter impinging against the inner face of the wall of the spherical member coöperating with such stem, adjacent to 80 the opening formed in said member, and exerting thereon an adverse leverage which, the attempt to deflect the chain being continued, will not only tend to unduly enlarge said opening, thus working against the attractiveness of the appearance of the chain as a completed article, but to enlarge the same sufficiently to permit the withdrawal 85 of said stem therefrom, thereby, and always to the disadvantage of the user, severing the chain. I purpose to overcome the foregoing objection to prior analogous chains. Again, in assembling the parts of prior 90 analogous chains, much difficulty necessarily attends the handling of the stock from which the separate connecting stems are formed,

and this even when such stock shall have been prepared for final severance into said connecting stems. The reason for this is, that said stock, ordinarily in the form of 5 wire of a suitable gage, presents, neither in its primary condition nor when prepared for ultimate severance into the separate connecting stems, as stated, no flattened surface capable of enhancing the convenience and 10 facility with which said stock may be handled, either by the hand of an operative, or by a mechanism which may be designed to that end. I purpose, also, to overcome this 15 objectionable feature of prior analogous chains.

In carrying out my invention, reference being had to the accompanying drawings, I 20 make use of a plurality of hollow, approximately spherical members 2, spun or drawn to form, each from an appropriate blank of thin metal, or other suitable material, as in common practice, said spherical members being flexibly united, each to its adjacent neighbor, at either side thereof, by means of 25 a connecting stem 3. These stems are formed from stock, primarily in the form of wire of an appropriate gage; and in the preparation of said stock to this end, the same is oppositely flattened, under pressure, parallel 30 with the axis thereof, and at suitable intervals therealong, as clearly indicated in Fig. 4 of the drawings. During the foregoing flattening operation, whereby opposite flattened faces are formed, the material under 35 pressure is forced or expanded laterally, thereby resulting in the formation of opposite segmental shoulders 4, at the opposite extremities of each of the surfaces thus flattened, said shoulders being each not only 40 curved away from the axis of said stock, but by preference provided with an edge surface more or less rounded from one to the other of the flattened faces aforesaid. Also, and by preference, during said flattening operation, the flattened portions of the 45 stock, each midway the length thereof, and as at the points 5, are nearly but not completely severed. In assembling the parts of my improved chain, each of the members 2 50 is drawn up or spun into a hollow, spherical form, around said stock, previously prepared as hereinbefore described, and in a manner to embrace within its interior one of the flattened portions, aforesaid, thereof, and 55 likewise the respective segmental shoulders adjacent thereto. Then, under due manipulation of the parts thus assembled, the stock aforesaid may be completely severed at the points 5; whereupon the stems 3, thus 60 segregated, become yieldingly locked, each within the spherical member at either end-portion thereof, and a bead-chain, durable, attractive in appearance, and of greatly enhanced flexibility, is formed.

Attention is here called to the fact that a 65 deflecting strain applied to any of the stems 3 at any angle between the opposite segmental shoulders thereof, will result in a much greater deflection of said stem relatively to either of the spherical members co-operating therewith, and accordingly insure a much greater general flexibility of the completed chain, than where a shoulder continuously encircling the stem is employed; 70 this, for the reason that there is nothing in 75 the nature of a shoulder, at either side of said stem and between the opposite segmental shoulders thereof, to impinge against the wall of the adjacent spherical member. Further, when the segmental shoulders are 80 used and rounded transversely, as hereinbefore explained, the same have, each, approximately a point contact with the wall of the spherical member co-operating therewith, which still further enhances the degree 85 to which any of the stems 3 may be deflected relatively to the spherical member co-operating herewith. Still further, the flattened heads or faces of the stems 3 which I make 90 use of, insure marked facility and convenience in the handling of the same, whether by manual effort, or a mechanism specially designed for the purpose, since a holding force may be more readily applied to a flattened surface than to a rounded one. 95

It will be seen that my improved bead-chain is well adapted for the purposes for which it is intended, and that the same may be modified to some extent, particularly as regards the employment of one or more flattened faces at the respective end-portions of each of the stems aforesaid, the rounding of the segmental shoulders aforesaid, or either of them, transversely, and other minor details of the general construction, without 100 materially departing from the spirit and principle of my invention. 105

I claim:

1. As a new article of manufacture, a 110 bead-chain consisting of a plurality of hollow, spherical members flexibly united successively by means of connecting stems, the latter being, each reduced diametrically at a suitable point therealong and affording segmental shoulders at the opposite end-portions thereof, the segmental shoulder at either end-portion of said stem being adapted to engage the inner face of the wall 115 of the spherical member immediately co-operating therewith. 120

2. As a new article of manufacture, a 125 bead-chain consisting of a plurality of hollow, spherical members flexibly united successively by means of connecting stems, the latter being, each oppositely flattened longitudinally, at the opposite end-portions thereof, and affording, at said opposite end-portions, respectively, opposite segmental

shoulders, the shoulders at either end-portion of said stem being adapted to engage the inner face of the wall of the spherical member immediately coöperating therewith.

5 3. For a bead-chain, a connecting stem flattened longitudinally at the opposite end-ports thereof, and affording segmental

shoulders at said opposite end-portions, respectively.

WILLIAM W. BRADLEY.
